UNITED STATES PATENT OFFICE.

CHARLES I. LATTIG, OF ROCHESTER, NEW YORK, ASSIGNOR, BY MESNE ASSIGNMENTS, TO LANGSLOW-FOWLER COMPANY, OF ROCHESTER, NEW YORK, A CORPORATION OF NEW YORK.

SCHOOL-CHAIR.

1,298,519.

Specification of Letters Patent.

Patented Mar. 25, 1919.

Application filed April 14, 1913. Serial No. 760,874.

To all whom it may concern:

Be it known that I, CHARLES I. LATTIG, a citizen of the United States, residing at Rochester, in the county of Monroe and State of New York, have invented certain new and useful Improvements in School-Chairs; and I do hereby declare the following to be a full, clear, and exact description of the same, reference being had to the accompanying drawings, forming a part of this specification, and to the reference-numerals marked thereon.

My present invention has for its object to provide an improved form of combined chair and writing desk, which is particularly adapted to be used as a study or school chair, the parts of which are adjustable to accommodate persons of different stature.

My invention has for its further object to provide an improved framing construction adapted particularly for chairs of this character, consisting in the positioning of one of the front legs of the chair ahead of the forward edge of the seat for the purpose of increasing the stability of the chair and rendering it less liable to be overturned.

To these and other ends the invention consists in certain improvements and combinations of parts all as will be hereinafter more fully described, the novel features being pointed out in the claims at the end of the specification.

In the drawings:

Figure 1 is a side elevation of a chair constructed in accordance with my invention;

Fig. 2 is a front elevation thereof;

Fig. 3 is a top plan view, the desk lid being removed, and shown in plan view in Fig. 4;

Fig. 5 is an enlarged detail, vertical, sectional view taken on the line 5^x-5^x of Fig. 1, and

Fig. 6 is a similar view taken on the line 6^x-6^x of Fig. 5.

Similar reference numerals in the several figures, indicate the same parts.

In carrying out my invention it may be applied to any particular type or style of chair, the essential elements of which are shown in the illustrations as comprise the seat 1 and the front and rear pairs of legs a-a'; b-b' respectively. The rear legs are connected by the rail or frame piece b² and they are each connected with one of the

forward legs by the side pieces c-c' which are of unequal length, the longer one being preferably located at the right hand side of the structure so as to position the leg a somewhat in advance of the other leg a' as shown particularly in Fig. 1, thus providing a forwardly projecting bearing or support in advance of the forward edge of the seat 1. The usual front frame piece of the chair seat frame, indicated by d, extends beneath the forward edge of the seat parallel to the rail b², its ends being mortised or otherwise secured to the inner face of the rail c and the inner edge of the leg a'. The seat 1 is preferably made solid and constructed of wood and at one edge is provided with the forwardly extending projection 1^x, which overlaps the inner edge of the leg a and to which it is securely united, this arrangement affording a brace or bracket, which materially stiffens the upper end of said leg. The latter may also be further braced by a bracket d' secured to the face of the rail d near its lower edge as shown in Fig. 2.

The desk or writing table indicated by 2 is located at a convenient height above the chair seat and to afford a support for it, the end of the chair leg a is projected vertically a short distance as indicated by a² and also spaced therefrom and parallel to the leg is a frame piece a³ which is secured to the outer face of the rail c, its upper end being united to the upper extremity of the leg a by a cross plate a⁴. The leg a and the frame a³ are preferably made rectangular in cross section so that their side faces and front and rear edges combine to form parallel angular guides on which is movably mounted the vertically adjustable support 95 on which the desk is mounted.

The support for the desk comprises the vertical angle iron strips f-f' joined at their lower ends by the strap f², having their upper ends f³ and f⁴, respectively, bent into a horizontal position and extending transversely across the front of the chair. The portions f-f' of the support are connected at their upper ends by an angle iron guide g and their laterally projecting ends f³-f⁴ are similarly connected by a guide g', said guides being arranged parallel and extending forwardly relatively to the chair seat. The support is further strengthened by a plate h riveted to the parts f³ and f⁴ and 110

corner bracket plates $i-i'$ extending over the outer faces of the angle irons and riveted thereto, as shown in the several figures. The desk 2 is adjustably secured in position by 5 rails k and k' , which permit it to be adjusted either forwardly or rearwardly, as desired, the limitation of this movement being determined by a stop member 7 attached to the under side of the desk and co-operating 10 with the adjacent edges of the supporting members f^3 and f^4 , as shown in dotted lines in Fig. 4, and full lines in Fig. 6.

The vertical adjustment of the desk is preferably obtained by clamping nuts on the 15 bolts $m-m'$ carried on the leg a and guide piece a^3 , which project through elongated slots or apertures in the supporting members $f-f'$, shown particularly in Fig. 1.

A chair constructed in accordance with 20 my present invention possesses a particular advantage in that a firm and rigid construction is provided for the support of the desk which is disposed centrally of one end thereof and as the support itself comprises parallel members which are spaced apart, it is 25 capable of withstanding the twisting or torsional strains resulting from shifting the chair by grasping the desk, by carelessness on the part of the user when seating himself or in attempting to arise from the chair; or by reason of the load which may be applied to the desk; further, an important function may be ascribed to the positioning of the leg underlying the desk lid at a point 30 in advance of the other front leg of the chair, since this separates the bearing points on which the chair rests and affords additional stability to the structure without requiring greater floor space than must be 35 allotted to an ordinary chair equipped with a desk attachment.

I claim as my invention:

1. A freely movable school chair comprising a seat, two hind legs and a leg at a forward portion of the seat, a desk and a supporting frame therefor, said frame comprising a horizontal part extending in front of and above the seat and a vertical part at one end only, the vertical part being secured to the chair, the desk being entirely supported 45 on said supporting frame, thus providing a clearance on one side for ingress and egress, said chair having a base support immovable relatively to the chair and located in front of the seat, and which extends approximately to the front edge of the supporting frame preventing easy forward tipping of the desk and chair.

2. A freely movable school chair comprising a seat, two hind legs and a leg at a forward portion of the seat, a desk and a wide supporting frame extending from the chair to approximately the front of the desk, said frame comprising a horizontal and a vertical part of substantially the same width, the 60 horizontal part extending in front of and above the seat and the vertical part at one end only, the vertical part being secured to the chair, the desk being entirely supported on said supporting frame, thus providing a 65 clearance on one side for ingress and egress, said chair having a base support approximately the same width as the said frame located in front of the seat and extending approximately to the front edge of the supporting frame preventing easy forward tipping of the desk and chair.

CHARLES I. LATTIG.
